United States Patent Office

Des. 202,275
Patented Sept. 14, 1965

202,275

MOBILE

Marilea Sue Smith, 5508 Indianola, Indianapolis, Ind.

Filed June 30, 1964, Ser. No. 80,650

Term of patent 14 years

(Cl. D29—1)

FIG. 4.

FIG. 1 is a perspective view of a mobile embodying my new design;

FIG. 2 is a side elevation therof on smaller scale;

FIG. 3 is a rear elevation thereof;

FIG. 4 is an enlarged front elevation of a modified form of the mobile shown in FIG. 1; and

FIG. 5 is a side elevation of the mobile shown in Fig. 4. The rear side of the mobile shown in FIGS. 4 and 5 is a mirror image of the side shown in FIG. 4.

I claim:

The ornamental design for a mobile, as shown and described.
